STATISTICAL MACHINE

Arthur Thomas, Wallington, and Frederick Sidney Rhodes, Thornton Heath, England, assignors to Powers-Samas Accounting Machines Limited, London, England, a British company

Application January 13, 1951, Serial No. 205,841
In Great Britain February 2, 1950

10 Claims. (Cl. 209—110)

1

This invention relates to statistical machines and in particular to apparatus arranged to receive record cards delivered in succession from such machines.

In a statistical machine record cards are fed through the machine in succession after being fed from a magazine and are delivered from the machine into receivers, usually into the open top of a receiver. In some instances it may be desired to displace one or more cards with relation to the other cards contained in the receiver in order to direct the attention of the machine attendant thereto.

One example of an occasion when cards may be required to be displaced in the manner just described is when the statistical machine is a comparing machine in which pairs of cards are compared to determine whether certain information contained in each of the cards of a pair is identical. After the cards of the pair have been sensed they are delivered to different card receivers and should it happen that disagreement is found between the cards it is desired that each of the cards be examined to determine which of the cards is in error. To this end the cards, when delivered to their respective receivers, may be displaced with respect to the remaining cards in the receiver in order that at the end of the run the stacks of cards may be taken from the two receivers and those cards which are displaced can be taken therefrom and examined.

It is an object of the present invention to provide a mechanism for displacing cards in a receiver on receipt of a signal that a particular card is to be so displaced.

According to the invention there is provided in a statistical machine, apparatus to receive record cards delivered in succession from the machine, said apparatus comprising a card receiver to receive cards delivered into the top thereof, movable means to impede the trailing end of each card delivered to the receiver and retain the card in tilted position about its leading edge for a predetermined interval, card displacing means to engage and move a tilted card transversely of its direction of movement to the receiver, actuating means for said card displacing means, said actuating means including a normally active coupling and a trip member controlled by a function of the machine to render the coupling inactive and thereby prevent operation of the card displacing means, and means operable in timed relation with said actuating means to effect movement of said movable means

2

to a non-impeding position so that a tilted card is permitted to fall on to other cards in the receiver.

In order that the invention may be more clearly understood an embodiment thereof will be described by way of example with reference to the accompanying diagrammatic drawings in which:

Figure 1 is a pictorial illustration of apparatus according to the invention, and

Figure 2 is a detail of the apparatus shown in Figure 1 with the parts in positions different from those which they occupy in Figure 1.

The apparatus about to be described is intended for use with a machine for comparing record cards, the record cards being fed in pairs, one from each of two magazines, to two sensing devices which sense the record cards and transmit impulses representative of the sensed data to a comparing mechanism adapted to determine identity or lack of identity of the data contained in the pair of cards. The general arrangement of the sensing mechanism is preferably similar to that described in British specification No. 2,772/50 and the comparing apparatus is preferably that described in British specification No. 2,770/50.

After sensing the cards fed from the two sensing devices are fed in known manner to separate card receivers but in the succeeding description only the mechanism associated with one card receiver will be described in detail as the card displacing mechanism is the same for both receivers and is simultaneously actuated by mechanism hereinafter described. No description of the comparing mechanism is contained herein as this mechanism forms no part of the present invention.

Referring to the drawings, cards issuing from the comparing machine are delivered by rollers, not shown, in the usual manner into the top of a card receiver 1, the first card delivered into the receiver being received on a platform 2 supported on an axially movable stem 3 against the action of a spring 4 in well known manner. As the pile of cards builds up in the receiver the platform 2 descends under the weight of the cards and the cards delivered into the receiver in succession to the first card so delivered are successively received on the upper surface of the uppermost card in the receiver.

As can be seen from the drawing, the receiver is completely open at one side as indicated by the reference numeral 5 and the opposite side of the receiver is slotted or otherwise

formed to permit card displacing means to enter through that side of the container and engage the edge of a card in a manner to be described below. As the side 5 of the receiver is completely open, the card displacing means, which is shown in the drawing as a pusher 6, can move a card lengthwise so that it is displaced in relation to other cards which are contained in the receiver. In the present instance the apparatus is so constructed that on operation of the pusher 6 a card is moved lengthwise thereby for a distance of about one inch so that when a pack of cards is removed from the receiver any card which has been displaced by the pusher is clearly distinguished from the other cards which are relatively neatly stacked one above the other.

As a card is delivered into the top of the receiver it passes over movable means shown as a plate 7, which is in such a position that as the card falls into the receiver the leading end is engaged by the front wall of the receiver and is guided downwards either on to the platform 2 or on the upper surface of the card immediately preceding the card being delivered to the receiver. The plate 7 protrudes into the receiver to an extent such that it engages the under surface of the card being delivered into the receiver and impedes the trailing end of the card so that this end cannot fall into the receiver and the card is tilted in the receiver about its leading edge as shown in the drawing. The card is retained in this tilted position by the plate 7 until the comparing mechanism has determined whether or not there is identity between the card so delivered to the receiver and the other card with which it is paired and which has been similarly delivered to a second receiver. If the comparing mechanism should determine that there is a lack of identity between the compared portions of the cards, the pusher 6 is operated to move the card lengthwise through the open side 5 of the receiver. The plate 7 is then moved rearwards out of the path of the trailing end of the card thus permitting the trailing end to fall into the receiver. Conversely, of course, if the comparing apparatus determines that the compared portions of the cards are identical the pusher 6 is not operated but at the appropriate instant the plate 7 is moved rearwards to permit the trailing end of the card to fall into the receiver.

The plate 7 is mounted for reciprocation in a straight line path determined by guide elements 8 and 9 secured to the rear of the receiver and oscillation of the plate 7 is effected by an arm 10 secured to a rocking spindle 11 mounted in bearings 12, 13, also secured to the rear of the receiver. The upper end of the arm 10 is provided with a slot 14 which engages a pin 15 secured to the under side of the plate 7 and the rocking spindle 11 is rocked at each machine cycle by a cam 16 secured to a driving shaft 17, the cam 16 co-operating with a roller 18 carried by an arm 19 secured to the rocking spindle 11. A spring 20 tends to urge the plate 7 to its non-impeding position.

The pusher 6 is secured to a rock shaft 21 mounted in bearings 22, 23, secured to the card receiver and also mounted in these bearings is an intermediate spindle 24 which is connected with the rock shaft 21 by arms 25, 26 secured respectively to the rock shaft 21 and the intermediate spindle 24. The arm 25 is provided with a pin 27 which engages in a slot 28 formed in the end of the arm 26. When the intermediate spindle 24 is moved angularly, the movement

thereof is imparted through the arms 26, 25 to the rock shaft 21 so that, as viewed in Figure 1, the pusher 6 is rocked clockwise against the action of a spring 28a to effect displacement of a card in a direction transverse to that of its direction of movement into the receivers.

To one end of the intermediate spindle 24 is secured a bevel gear 29 which meshes with a similar bevel gear 30 secured to an operating spindle 31 mounted in bearings 32 fixed to the rear of the card receiver.

The opposite end of the operating spindle 31 has secured thereto an arm 33 which, when engaged by a pin 34 as will be described below, effects angular movement of the operating spindle 31 thereby operating the pusher 6.

The actuating means for the pusher 6 comprises, in addition to the mechanism just described, a first plate 35 and a second plate 36, the plates being disposed in parallel planes for movement relative one to the other as will be described below. The plate 35 has two studs 37, 38 extending laterally therefrom, the studs projecting through slots 39, 40 respectively formed in the second plate 36 and extending lengthwise thereof. The stud 38 is engaged by a slot 41 formed in the end of one arm 42 of a bell-crank lever pivoted at 43 to the frame of the machine, the other arm 44 of the bell crank lever supporting a cam follower 45 which co-operates with a pusher-operating cam 46 secured to the driving shaft 17. A spring 47 urges the first plate 35 to its inactive position.

The second plate 36 is provided with a driving pawl 48 pivoted at 49 to the plate 36 and a latch 50 to co-operate with the pawl is pivoted at 51 to the plate 36. A spring 52 urges the pawl and the latch towards each other. The latch and pawl, together with the stud 37, comprise a coupling which can be rendered active or inactive to permit or prevent the operation of the pusher 6, even though the first plate 35 is reciprocated lengthwise at each machine cycle through the operation of the pusher-operating cam 46.

As shown in Figure 1, the coupling is in its active position and a nose 53 on the pawl is hooked around the stud 37. As shown in Figure 1, the first plate 35 has already completed part of its forward movement so that the stud is brought into engagement with the nose 53 of the driving pawl 48 and a lobe 54 on the pusher-operating cam 46 causes the movement of the first plate 35 to be continued so that as the stud 37 engages the driving pawl 48 the second plate 36 is moved forward together with the first plate. During the forward movement of the second plate 36, the pin 34 engages the arm 33 and rocks it clockwise, thereby angularly moving the operating spindle 31 to effect operation of the pusher 6. On the return movement of the first and second plates, under the action of springs 47 and 55, the second plate 36 is arrested by a stud 56.

As has been mentioned above, it is desired to operate the pusher 6 only when a disagreement is detected between a pair of compared cards and it is not therefore desired that the arm 33 be rocked at each cycle of the driving shaft 17. Accordingly a trip member is provided to render the coupling inactive, and the trip member, as shown in the drawing, comprises a pin 57 extending laterally from a plate 58 secured to a link 59 the lower end of which is provided with a slot 60 by which the link 59 is guided for vertical movement relative to the second plate 36 by the co-operation of the slot 60 with a pin 61

extending laterally from the plate 36. The opposite end of the link 59 is connected to an arm 62 pivoted on a stud 63 secured to a part of the machine frame as indicated at 64.

The arm 62 also has connected thereto one end of a link 65, the opposite end of which is pivoted at 66 to an arm 67 secured to a bail-carrying shaft 68. The bail-carrying shaft 68 is rocked clockwise, as viewed in the drawing, each time an agreement is determined by the comparing mechanism but when disagreement is detected substantially no angular movement of the bail-carrying shaft occurs. Thus, on each agreement, rocking of the bail-carrying shaft 68 causes the link 65 to be moved downward, 15 rocking the arm 62 about the stud 63 and causing the link 59 also to be moved downwards so that the pin 57 engages the tail 69 of the driving pawl 48, rotating the pawl clockwise about its pivot 49 and raising the nose 53 out of the path of the stud 37, as shown in Figure 2. The clockwise movement of the pawl 48 brings a tooth 70 formed thereon into engagement with a corresponding tooth 71 formed on the latch 50 so that the pawl 48 is latched out of the path of the stud 37 and the coupling between the first plate 35 and the second plate 36 is rendered inactive. Accordingly, when the first plate 35 is moved forward by the pusher-operating cam 46, the studs 37 and 38 slide in the slots 39 and 40 so that relative movement between the plates 35 and 36 is effected and no movement of the plate 36 occurs. As the plate 36 is not moved lengthwise with the plate 35, the pin 34 does not engage and rock the arm 33 and accordingly the pusher 6 is not actuated.

When the apparatus is employed in conjunction with a comparing machine, two card receivers disposed one above the other are employed and on a disagreement each of the disagreeing cards is moved lengthwise in its respective receiver by a pusher 6. The movement of the pushers associated with the two magazines is simultaneous and this is effected by connecting the intermediate spindle 24 of the lower receiver with a similar spindle associated with the other of the two receivers. The spindle 24 has an arm 72 secured thereto and to the arm 72 is connected one end of a link 73, the other end of which is connected with an arm, not shown, secured to the intermediate spindle of the upper receiver. Thus, it will be understood, on rocking the intermediate spindle 24, the corresponding spindle associated with the other of the two receivers is also rocked and the two pushers 6 are simultaneously operated.

The other of the two receivers is also provided with a plate similar to the plate 7 described above and this other plate is operated simultaneously with the plate 7. To this end, the said other plate has connected thereto the upper end of a link 74, the lower end of which is connected at 15 to an arm 76 secured to the rocking spindle 11. Accordingly, operation of the upper and lower plates 7 is simultaneously effected by the action of the cam 16.

We claim:

1. In a statistical machine, apparatus to receive record cards delivered in succession from the machine, said apparatus comprising a card receiver to receive cards delivered into the top thereof, movable means to impede the trailing end of each card delivered to the receiver and retain the card in tilted position about its leading edge for a predetermined interval, card dis-

placing means to engage and move a tilted card transversely of its direction of movement to the receiver, actuating means for said card displacing means, said actuating means including a normally active coupling and a trip member controlled by a function of the machine to render the coupling inactive and thereby prevent operation of the card displacing means, and means operable in timed relation with said actuating means to effect movement of said movable means to a non-impeding position so that a tilted card is permitted to fall on to other cards in the receiver.

2. Apparatus according to claim 1, wherein the movable means is mounted for reciprocation in a straight line path by a link mechanism operated by a cam mounted on a driving shaft arranged also to operate the actuating means for the card displacing means.

3. Apparatus according to claim 2, wherein the card displacing means comprises a pusher mounted for angular movement with a rock shaft and the actuating means includes an intermediate spindle coupled to the rock shaft to effect rocking thereof, an operating spindle geared to the intermediate spindle, and a reciprocable driving element to effect angular movement of the operating spindle, said driving element being operated by a pusher-operating cam on said driving shaft.

4. Apparatus according to claim 3, wherein the reciprocable driving element comprises a first and a second plate, the plates being disposed in parallel planes for movement relative one to the other, said first plate being arranged for positive reciprocation by said pusher-operating cam during each cycle of the driving shaft, and the coupling arranged to couple the second plate to the first plate and when active causing an abutment on the second plate to engage an arm secured to said operating spindle to effect angular movement of the rock shaft.

5. Apparatus according to claim 4, wherein the coupling comprises a stud extending laterally from the first plate for movement in a slot in the second plate, a driving pawl and a latch pivotally mounted on the second plate to operate from opposite sides of the stud, the pawl and latch being spring-urged towards each other to a position at which the pawl is engaged by the stud to render the coupling active.

6. Apparatus according to claim 5, wherein a trip member is operable to engage said pawl and move it about its pivot to a position at which it is moved out of the path of the stud and in which it is retained by said latch to render the coupling inactive.

7. The method of segregating selected cards in a card aligned stack comprising the steps of tilting each card with respect to the stack as it is fed thereto, transversely displacing selected cards out of stack alignment, and then releasing said tilted card to fall on to said stack.

8. In a statistical machine, a card receiver including a yieldable support upon which cards drop one at a time for stacking alignment, means for impeding the fall of a card at one edge thereof to position the card in tilted position at the top of the stack, means for shifting some of the tilted cards out of alignment with the stack, and means for moving said impeding means for releasing said tilted cards.

9. In a statistical machine the combination with a card receptacle into which cards are dropped one at a time for aligned stacking on a

yieldable support in the receptacle; of means for impeding the drop of a card at one edge thereof for support at the opposite edge in tilted position at the top of the stack, means for shifting selected cards out of stack alignment while they are held in tilted position and means for moving said impeding means to drop the cards from tilted position to a position on top of said stack.

10. In a statistical machine a plurality of card receptacles into which cards are dropped one at a time for aligned stacking, a yieldable card support in each receptacle, means in each receptacle for impeding the drop of a card at one edge thereof for support at the opposite edge in

5 tilted position at the top of the stack, means associated with each magazine for shifting selected cards out of stack alignment while they are held in tilted position, means for moving each of said

10 impeding means to drop the cards from tilted position to a position on top of the stack, means for connecting the impeding means of each magazine for operation in unison and means for connecting the shifting means of each magazine for operation in unison.
